UNITED STATES PATENT OFFICE

107,505

DESIGN FOR A HANDBAG

Henri Felmann, Chicago, Ill.

Application November 16, 1937, Serial No. 72,918

Term of patent 3½ years

To all whom it may concern:

Be it known that I, Henri Felmann, a citizen of the United States of America, residing in Chicago, in the county of Cook, State of Illinois, have invented a new, original, and ornamental Design for a Handbag, of which the following is a specification, reference being had to the accompanying drawing, forming part thereof, wherein,

The rear portion of the handbag is identical in appearance to the front.

The characteristic feature of my design resides in the central loops to which the handles are attached extending over the roll-top portions in combination with the bag as shown.

I claim:

The ornamental design for a handbag, substantially as shown and described.

HENRI FELMANN.
